W. H. MUZZY,
FUEL FEEDING SYSTEM,
APPLICATION FILED FEB. 26, 1917. RENEWED NOV. 9, 1918.

1,325,571.

Patented Dec. 23, 1919

UNITED STATES PATENT OFFICE.

WILLIAM H. MUZZY, OF DETROIT, MICHIGAN, ASSIGNOR TO STEWART-WARNER SPEEDOMETER CORPORATION, OF CHICAGO, ILLINOIS, A CORPORATION OF VIRGINIA.

FUEL-FEEDING SYSTEM.

1,325,571.

Specification of Letters Patent. Patented Dec. 23, 1919.

Application filed February 26, 1917, Serial No. 151,023. Renewed November 9, 1918. Serial No. 261,940.

To all whom it may concern:

Be it known that I, WILLIAM H. MUZZY, a citizen of the United States, residing at Detroit, in the county of Wayne and State 5 of Michigan, have invented certain new and useful Improvements in Fuel-Feeding Systems, of which I declare the following to be a full, clear, and exact description.

This invention relates to improvements 10 in fuel feeding systems for automobiles or the like and has more particular relation to improvements in devices of the character shown and described in my Patents No. 1,201,077 issued October 10, 1916, and No. 15 1,222,235, issued April 10th, 1917.

One of the several objects of the invention is to provide improved means whereby in a vacuum system such as shown in my aforesaid patent, there will be no chance of the 20 system becoming exhausted by all of the gasoline passing out of the same, and thus become inoperative until again provided with the working quantity of gasoline.

Another object of the invention is to provide improved means for suspending the 25 operation of the pumping devices when the system becomes fully charged and so hold it until sufficient of the fuel has been used to again bring it into operation.

Another object of the invention is to so 30 construct the tank and connected devices that the vacuum chamber proper will be permanently sealed with no devices therein that will require any attention and thus do 35 away with all packing gaskets or other detachable packing means which are required when the vacuum chamber is not permanently sealed.

Another object of the invention is the 40 provision of an improved valve or dam for the obstruction of the several pipes in the system.

Further objects of the invention are simplicity of construction and the provision of 45 parts which may be stamped from sheet metal and assembled without machining or being formed with any fine fitting points or joints.

In carrying these and other objects of the 50 invention into effect I utilize certain constructions, combinations and arrangements

of parts all of which will be hereinafter more particularly set forth and claimed.

In the accompanying drawings forming 55 part of this specification;

Figure 1 represents a central vertical section through a vacuum fuel feeding tank embodying my invention, and,

Fig. 2 represents a detail vertical section of the lower end of one of the pipes showing 60 my improved form of valve or dam.

In general terms the invention may be said to operate by the suction from the manifold of the engine and draw the gasoline from a relatively low main fuel tank at the 65 rear of the machine in intermittent pumping operations as described and shown in my aforesaid patent and reference is made to the same for any further description of this general operation desired. After being 70 drawn into the elevated tank the gasoline is fed to the relatively lower carburetor of the engine by gravity. This is all old and well known in the art.

In the aforesaid drawings 1 represents the 75 vacuum chamber or tank and 2 the supply chamber or tank. The vacuum chamber is suitably connected to the manifold of the engine by a pipe 5, having a small opening 16 at the end which enters the tank, where- 80 by the air is exhausted in this vacuum tank so that the atmospheric pressure on the main tank at the rear will cause the gasoline to pass up a pipe 6 and enter the vacuum chamber through this pipe which is suitably connected to the top of said chamber or tank and extends a slight distance down into the same. The tank 1 is formed from a single stamping and is formed with a flange 85 17 at its lower edge which rests upon a flat plate 18 forming the permanent bottom of the tank. A ring 19 laid on the outer edge of the plate 18 forms a channel 20 into which hot solder or brazing compound is 90 run to permanently unite the plate and tank 95 and as this tank contains no moving parts there is no occasion to break this joint again. All packing gaskets are thus done away with.

The tank or chamber 2 is similarly formed from a single stamping having an 100 attaching flange 21 at its upper edge by which it is attached to the plate 18 by means

of screw bolts 22, a flange 23 of the sealing receptacle, 3, being interposed to support the latter in position about the trapping chamber or siphon cup 4. This latter cup 5 is in turn supported by the vent pipe 7 which extends from near the top of the vacuum chamber 1, down through the plate 18, to which it is suitably attached, and passes through the bottom of said cup 4. 10 The pipe where it passes through the plate 18 and the cup 4 is provided with compression attachments by which it is secured in position. These compression attachments are used at other locations in the tank but 15 as they are old and well known in the art no further description of the same is necessary.

The feeding pipe 8 extends from the plate 18 to near the bottom of the trapping chamber of siphon cup 4 and is held in position by a similar compression coupling. This pipe is provided at its lower end with a valve which consists of a flat disk 13 and a hook stem 14 supported and guided by a 20 cross pin 15 mounted in the pipe. The lower end of the vent pipe 7 is provided with a similar valve and the pipe in this case is provided with a small control opening 24 near its lower end. This opening 25 determines the length of the pumping operation as only a certain amount of the gasolene in the cup 3 can pass through the same and a predetermined time must elapse before the cup can be emptied of the gasolene 30 which passes into it from the siphon 9 which is suitably mounted in the trapping chamber of siphon cup 4. The size of the siphon is such that the gasolene from the cup 4 is discharged more rapidly than the 35 vent pipe 7 can take it up and the pipe is thus completely choked and any air cut off from the chamber 1.

A feed pipe 10, having one of the valves or dams 13, at its lower end projects through 40 the plate 18 to which it is suitably attached. This pipe extends to near the bottom of the chamber 2 and up into the chamber 1 to a point slightly above the working level shown by the line $a-b$ in Fig. 1. As this 45 pipe 10 is the only means by which gasolene may pass from the chamber 1 to the chamber 2 it will be seen that the gasolene in the chamber 1 below the line $a-b$ will always be retained as a working quantity in tanks 50 1 or sealing receptacle 3 and trapping chamber 4, and cannot be drained from the tank under any circumstances, even when the chamber 2 is drained by the exhaustion of the main tank or for other reasons.

The lower end of the feed pipe 10 is 55 formed with a small notch 25 cut in its lower edge to permit a small quantity of gasolene to pass into the pipe at each pumping operation so that the weight of this gasolene in this pipe will cause the gasolene

in the chamber 1 to pass down the pipe when air passes up the pipe 7, that is of course provided that the level of the gasolene in the vacuum chamber 1 is above the upper end of the pipe. 70

The atmosphere air pipe 11 passes from the top of the tank to which it is suitably attached down through the vacuum chamber 1 and the plate 18 to which latter it is also suitably attached and thus gives the 75 chamber 2 atmospheric pressure. This pressure is also communicated to the sealing receptacle 3 through openings 28 near its upper end and to the trapping chamber 4 through openings 26 also near its upper end. 80

Openings 27 are also formed near the upper end of the sealing receptacle 3 but below the level of the openings 26 and 28, to allow the gasolene in the chamber 2 to pass into the receptacle 3 when the maximum 85 working level in the chamber is reached. This level is indicated by the line $e-f$ in Fig. 1.

The operation of the devices are as follows:

When the engine is started the operating gasolene is all in the sealing receptacle 3 and trapping chamber 4, to which it has run when the engine was stopped and the vacuum broken in the vacuum chamber 1. 90 The operation of the engine establishes a vacuum in the chamber 1 and the valves or dams on the pipes, 7, 8 and 10 immediately snap closed, and the gasolene starts to pass upward through the vent pipe 7 because of the opening 24 therein and any slight amount that may pass the dam itself. At the same time gasolene will pass into the feed pipe 10 through the notch 25 and perhaps slightly around the valve itself but 95 only in sufficient quantity to about fill the pipe during the time that the pumping operation continues. 100

The vent pipe 7 then draws all of the gasolene out of the sealing receptacle 3 and air starts to pass up the pipe and breaks the vacuum in the vacuum chamber 1. All the gasolene that was contained in the sealing receptacle 3 is returned to the vacuum chamber 1 and in addition the main feed pipe 6 110 has added about an equal quantity from the main tank. The gasolene level will now be 115 above the upper end of the pipe 10 and as air continues to pass up the pipe 7, gasolene will flow down both the pipes 8 and 10, the pipe 10 having meantime been filled through the notch 25 so as to have a pulling "head" when the vacuum is broken. When the trapping chamber 4 is filled by the gasolene passing down the pipe 8 the siphon 9 120 operates and discharges a predetermined quantity of gasolene into the sealing receptacle 3. This quantity discharged is the working medium and keeps the vent pipe 7 sealed for a predetermined time for pump- 125 130

ing. The pumping operations follow each other in rapid succession until the gasoline in the chamber 2 rises to the level *e-f* when it discharges through the openings 27 into the sealing receptacle 3. As a slight amount of gasoline passes thus into the sealing receptacle the pipe 7 is momentarily sealed and the gasoline drawn up into the vacuum chamber 1 when the pipe 7 is again unsealed. While the pipe remained sealed the downward flow through the feed pipes 8 and 10 is arrested and then as the vent pipe 7 clears again, resumed. This arresting of the flow of the gasoline into the trapping chamber 4 considerably prolongs the filling of this chamber and the starting of the next pumping operation. These operations automatically balance the amount of gasoline being used by the engine and passing out of the pipe 12 to the carburetor. If by any chance the pumping operations should gain on the amount being used by the engine, as sometimes might happen on very steep down grades then the surplus is returned to the main tank by the siphon effect of the end of the pipe 6 which projects down into the vacuum chamber 1 a certain distance.

The upper end of the pipe 11 is protected by an apertured cap 29.

It will be seen from the above that the tank cannot exhaust itself so that it becomes inoperative as many tanks at present on the market do as all the valves or dams are always covered by gasoline and thus rendered air tight even though the tank is otherwise empty. It has been found by experiment that even nicely ground gravity valves will leak air when uncovered and applicant therefore always keeps all valves or dams covered by the gasoline so that the tank is ready to pump at all times.

It will be observed that the pipe 12 projects up into the tank 2 to the level *c-d* so that the lower end of the pipe 10 is always covered even if the tank becomes otherwise depleted for any cause.

It will also be seen if for any cause the pumping decreases in volume so that the amount pumped is not sufficient to equal the amount being used by the engine, that the pumping cycles still continue even after the tank is otherwise exhausted. By this means in ascending steep grades the tank will continue to pump with its maximum efficiency even after the supply in the chamber 2 is greatly decreased. In many other systems at present on the market the operation of the tank will stop or be suspended in its cycle and the lower supply chamber entirely depleted of gasoline while the upper vacuum chamber has not enough gasoline to complete its cycle and descend to the lower chamber. With the present improvements the operation of the cycle goes on just the same with-

out any definite amount being pumped from the main tank and what little may be pumped in a cycle is periodically discharged into the supply chamber 2. This operation keeps the machine going much longer than one in which a definite amount of gasoline must be pumped from the rear tank before the pumped quantity can be discharged into the supply chamber.

It will of course be understood that all of the valves 13 may be omitted if desired and the devices still operate but not with the same efficiency. In such a practice the pipes 7, 8 and 10 would be made smaller to retard the flow of gasoline therethrough.

The level *g-h* is always maintained in the trapping chamber to seal the lower end of the pipe 8.

The operation of this tank is entirely automatic and continuous and the pumping operations follow each other in rapid succession except when suspended by the level in the tank 2 reaching a point where the gasoline passes through the openings 27 and intermittently chokes the air vent pipe 7 and causes the trapping chamber 4 to fill with a step by step flow from the feed pipe 8.

It will also be seen that the present improvements do away with all tank cover gaskets that must be air tight and that require fine machine work of the adjoining parts and substitute a permanently sealed chamber that contains nothing that must be inspected or adjusted. In dealing with a tank that must be air tight to resist a vacuum this is of particular advantage as any slight air leaks at once destroy the operativeness of the tank.

The valves 13 are practically trouble proof as they do not always seat on the same portions of the disks and thus automatically clean themselves and dislodge any very small particles of dirt that might lodge on them. Further any leakage does not render them inoperative and the pumping operation continues until the obstruction is finally washed away or knocked off by the operation of the valve or dam. Whenever the vacuum in the chamber 1 is broken all the valves 13 drop to their lower positions by gravity and when the suction is again established they are drawn closed both by the suction and by the stream of gasoline that attempts to pass into each pipe.

Having thus described my invention what I claim as new and desire to secure by Letters Patent is:

1. In a device in which liquid is alternately lifted from a lower source into a higher chamber by suction, and discharged therefrom upon relief of the suction, the method of timing the alternation of suction and relief therefrom which consists in producing a circulation of a determined quantity

- of liquid in an endless path which comprises the suction-relieving air inlet, and sealing and unsealing said inlet by the liquid alternately occupying and vacating said 5 inlet as said liquid courses in its endless path.
2. In a liquid feeding apparatus in which the liquid is lifted by suction from a lower source to a higher vacuum chamber and delivered from the vacuum chamber upon relief of the suction therein, feed connections leading from the apparatus; the means for the lifting and delivery mentioned, comprising, in combination with a vacuum chamber, 10 devices for governing the suction and relief thereof, consisting of a sealing receptacle into and from which a determined quantity of liquid is alternately delivered by gravity and withdrawn by suction, the receptacle being closed against escape of the liquid up to a height for containing said determined quantity, and an air vent pipe for the vacuum chamber which has its intake in said receptacle in a position to be submerged 15 and sealed by the liquid delivered into said receptacle, and constituting the suction outlet thereof.
3. In the structure defined in claim 2 foregoing, the channel for withdrawing the liquid from the vent-pipe-sealing receptacle being the vent pipe itself through which the liquid is sucked from the receptacle into the vacuum chamber.
4. In the construction defined in claim 2 foregoing, the vent-sealing receptacle being connected with the vacuum chamber for deriving its supply of liquid by gravity from the latter.
5. In the structure defined in claim 2 foregoing, a trapping chamber which receives liquid by gravity flow from the vacuum chamber and from which said liquid is supplied to the vent-sealing receptacle upon the rise of liquid to a predetermined height in the trapping chamber.
6. In the structure defined in claim 2 foregoing, a trapping chamber to which the liquid is directly supplied from the vacuum chamber and from which it is supplied to the vent-sealing receptacle upon its rise to a predetermined level in the trapping chamber.
7. In the structure defined in claim 2 foregoing, a trapping chamber to which the liquid is directly supplied from the vacuum chamber, and a siphon through which said liquid is supplied from the trapping chamber to the vent-sealing receptacle.
8. In the construction defined in claim 2 foregoing, the vent-sealing receptacle and the lower part of the vacuum chamber being together comprised in a circuit or endless path in which the sealing liquid moves in a cycle, the remainder of said circuit comprising the vent pipe for conducting the liquid 60 from the receptacle back to the vacuum chamber; a trapping chamber in which said receptacle is situated; a duct leading from the bottom of the vacuum chamber to the lower part of the trapping chamber, the sealing receptacle being connected with the trapping chamber for receiving the liquid therefrom upon the rise of the liquid to a predetermined level in said trapping chamber.
9. In the structure defined in claim 2, connections by which the sealing receptacle receives liquid from the vacuum chamber; a liquid fuel supply chamber, and connections by which it receives liquid from the vacuum chamber independent of the connections 70 from the vacuum chamber to the sealing receptacle.
10. In the structure defined in claim 2, a liquid fuel supply chamber; connections by which the sealing receptacle receives liquid from the vacuum chamber, and independent connections by which the liquid fuel supply chamber also receives liquid from the vacuum chamber, the latter connections leading 80 from a higher point in the vacuum chamber 85 from the former.
11. In a liquid fuel feeding apparatus in which the liquid is lifted by suction from a lower source to a higher vacuum chamber, and delivered from the vacuum chamber 90 upon relief of the suction therein; feed connections leading from the apparatus, and means for such lifting and delivery, comprising in combination with a vacuum chamber, devices for governing the suction 95 and relief thereof adapted to cause said suction and relief to recur in definite cycles, independently of the quantity of liquid lifted into the vacuum chamber or fed away from the apparatus, a liquid fuel supply chamber 100 which receives its supply from the vacuum chamber, the cycle-governing devices comprising a relief control receptacle independent of the fuel supply chamber, and means intermediate the vacuum chamber 105 and the relief control receptacle for timing the intervals and duration of the relief.
12. In the structure defined in claim 2, connections by which the sealing chamber is supplied with liquid from the vacuum 110 chamber, and a movable dam in said connections.
13. In the structure defined in claim 2, connections by which the sealing receptacle is adapted to receive liquid both from the 115 vacuum chamber and from the liquid fuel supply chamber.
14. In the structure defined in claim 2, a unitary tank structure which comprises the vacuum chamber and contains the sealing 120 receptacle, a liquid fuel supply chamber also contained in said unitary tank structure, which sealing receptacle and said supply chamber having liquid communication with each other, said communication with 125 130

said receptacle being at the upper part thereof.

15. A tank for fuel feeding systems comprising a vacuum chamber permanently soldered closed, a supply tank into which the vacuum chamber discharges detachably connected to the same and having atmospheric communication and control devices including movable parts and located wholly with 10 in the supply tank so that they may be inspected or repaired at will without breaking any solder-sealed joints.

16. In the construction defined in claim 2, devices for governing the recurrence of 15 suction and relief in definite cycles comprising the sealing receptacle and a trapping chamber; a liquid fuel supply chamber which receives liquid from the vacuum chamber, the trapping chamber having connections by which it receives liquid from 20 the vacuum chamber, an air vent pipe leading from the upper part of the vacuum chamber to the lower part of the sealing chamber through which liquid may be 25 sucked from the sealing chamber back into the vacuum chamber; the liquid communication of the vacuum chamber with the liquid fuel supply chamber being at a higher level than communication with the trapping 30 chamber, the latter chamber having no outlet below a predetermined point except by the means by which it delivers liquid into the sealing receptacle, said receptacle having no liquid exit except that mentioned leading back into the vacuum chamber, and the vacuum chamber having no liquid exit between the levels of communication of the liquid fuel supply chamber and the trapping chamber respectively, 35 whereby a predetermined quantity of liquid trapped in the lower part of the vacuum chamber and the trapping chamber and sealing receptacle is without avenue of escape 40

after such quantity is once delivered into the vacuum chamber.

17. In a fuel feeding system, the combination with a tank having a vacuum chamber and a liquid fuel supply chamber, of means for creating a vacuum in the vacuum chamber, a fuel supply connection to the vacuum chamber, and control devices for creating cycles of pumping action and discharging means for the vacuum chamber to the supply chamber, said chambers and control devices constructed and coöperating to permanently trap a certain operating quantity of liquid fuel in the vacuum chamber and the control devices, and prevent the discharge of said quantity from the tank. 55

18. In a fuel feeding system the combination with a tank having a vacuum chamber and a supply chamber, of means for creating a vacuum in the vacuum chamber, a fuel supply connection for the vacuum chamber, control devices for creating cycles 60 of pumping and constructed to retain a certain fixed quantity of liquid fuel permanently trapped against discharge from the tank; and an independent discharge between the vacuum tank and the supply tank. 70

19. In a fuel feeding system the combination with a tank having a vacuum chamber and a supply chamber, of means for creating a vacuum in the vacuum chamber, a fuel supply connection for the vacuum chamber, and control devices for creating cycles of pumping and constructed to retain a certain fixed quantity of fuel permanently trapped against discharge from the tank. 75

In testimony whereof I affix my signature 80 in the presence of two witnesses.
